UNITED STATES PATENT OFFICE.

MATTHEW J. MORGAN, OF CHICAGO, ILLINOIS.

CAR-COUPING UNCOUPLING DEVICE.

1,111,080.

Specification of Letters Patent. Patented Sept. 22, 1914.

Application filed December 15, 1911. Serial No. 663,077.

To all whom it may concern:

Be it known that I, MATTHEW J. MORGAN, a citizen of the United States, residing at Chicago, in the county of Cook and State 5 of Illinois, have invented a new and useful Improvement in Car-Coupler Uncoupling Devices, of which the following is a specification.

My invention relates to the uncoupling arrangement in connection with the knuckle lock of a car coupler; ordinarily the uncoupling arrangement consists of an uncoupling rod attached to the end of the car, by means of two brackets commonly called pinlifter 10 brackets, in a location slightly above the top plane of the coupler; one end of the uncoupling rod being at or adjacent to the center of the car,—the other being at or adjacent to the outer edge of the car. The uncoupling rod is made of ordinary round iron or steel of suitable dimension, being bent at a right angle downward on the outer end to form the operating arm and the inner end of the uncoupling rod is bent at a 15 right angle outward from the car to form the lifting arm; said lifting arm being flattened on the outer free end to permit drilling of a hole through the same, of sufficient dimension to receive the clevis pin. The uncoupling rod is attached to the knuckle lock of the coupler by means of two clevises and a link or chain, one clevis is attached to the outer free end of the lifting arm of the uncoupling rod,—the other being attached 20 to the knuckle lock. The clevises are connected by means of the link or chain. In the operation of the coupler, the link or chain, as the case may be, and clevises when in their normal position are slack and liable to become entangled or jammed so as to shorten and cause breakage of the link or chain, or other parts of the uncoupling device, and also the clevises being of a convenient size, for other purposes, are frequently surreptitiously removed while the cars are standing at way stations and in the yards, which results in a violation of the safety appliance laws of the United States.

My invention has for its object to obviate those features and consists in features of novelty as hereinafter described and claimed, reference being had to the accompanying drawing forming a part of this specification, whereon—

Figure 1 shows a top view, Fig. 2 a front view and Fig. 3 a side elevation of the de-

vice as applied to the knuckle lock of a car coupler, and arranged on the end of a car body in the usual manner. Figs. 1 and 2 show the end of a car body, upper part and right side broken away.

Like letters and numerals of reference denote like parts in all the figures.

(a) represents a car coupler of the ordinary automatic type, arranged relatively to the car body (b), in the usual well-known manner and having the knuckle lock (c), to the head, of which in the present case is attached lifting rod (d) by means of a hook on lower end of said lifting rod (d). In the uncoupling rod brackets (e) fixed to the end of the car body (b) is mounted and adapted to rotate the horizontally arranged uncoupling rod (g). The lifting arm (1) projects forward from the inner end of uncoupling rod (g) over and in the vertical plane of knuckle lock (c). From the outer end of lifting rod (g) at or adjacent to the side of the car body (b) projects downward an operating arm or handle (2).

For connecting the lifting arm (1) to the knuckle lock (c), I substitute for the clevises and link or chain of the ordinarily constructed uncoupling arrangement heretofore described, lifting rod (d) operating in a vertical position and in the vertical plane of knuckle lock (c), the lower end of which is attached to knuckle lock (c) by means of hook (3) formed on said lower end of lifting rod and of suitable size and shape that will permit of the lateral motion of the coupler without becoming detached from said knuckle lock. At the upper end of lifting rod (d) there is formed an elongated eye (4), which is of suitable dimensions to permit of the lateral and backward and forward motion of the coupler when car is in motion. The elongated eye (4) on upper end of lifting rod (d) operates within eye (5) formed on the end of lifting arm (1). The eye (5) on end of lifting arm (1) is of suitable form and dimensions to allow free play of lifting rod (d) according to the backward and forward or lateral motion of the coupler when car is in motion. By this construction, assuming the coupler (a) to be coupled to an adjoining car and locked by the knuckle lock (c), on releasing the operating arm (2) the end of lifting arm (1) will drop to the position indicated in Fig. 3. A sufficient section of elongated eye (4) of lifting rod (d) will extend above

105
110

lifting arm (1) to allow for the play of the 5
coupler caused by the rearward and forward
motion or lateral motion of coupler when
car is in motion, thus preventing tension and
consequential breakage of the parts of the
5 uncoupling arrangement, or in the alterna-
tive, the uncoupling of the coupler. Accom-
plishing this purpose entirely obviates
the necessity of elevises and link or chain.
10 What I claim as my invention and desire
to secure by Letters Patent, is—

In combination, a car, a coupler, a hori-
zontal rotatable rod secured to the end of
the car, said rod having at its inner end an
arm projecting outwardly over the coupler,
a closed eye upon said arm, a single link con-
necting said arm and the lock of said cou-
pler, said link being provided at one end
with a vertically elongated loop which fix-
edly secures said link to and normally ex-

tends a distance above and below the closed
eye in the projecting arm to permit longi-
tudinal movement of the coupler without
strain on said outwardly projecting arm and
having at its other end a hook which en-
gages an eye in the coupler lock, said hook
being formed as an open eye whereby the
lock and link may be attached or detached
without removing said lock from the coupler
or removing said rod from the end of the 30
car or detaching said link from the rod, sub-
stantially as described. 25

In testimony whereof I have signed my
name to this specification in the presence of
two subscribing witnesses.

MATTHEW J. MORGAN.
